UNITED STATES PATENT OFFICE.

JAMES E. JEWELL, OF KANSAS CITY, MISSOURI.

TOY.

1,242,194.

Specification of Letters Patent.

Patented Oct. 9, 1917.

Application filed April 16, 1917. Serial No. 162,560.

To all whom it may concern:

Be it known that I, JAMES E. JEWELL, a citizen of the United States, residing at Kansas City, in the county of Jackson and State of Missouri, have invented certain new and useful Improvements in Toys, of which the following is a specification.

This invention relates to toys of that general class comprising an object to be revolved, a drum to be turned in one direction by a pull cord, a ratchet mechanism, and a spring connected to the drum to rotate the same backward when the pull on the cord is relaxed, to rewind the latter and at the same time, through the ratchet mechanism effect rapid rotation of said object.

Heretofore all devices of this general class as far as applicant has been able to learn, are objectionable in that the drums are journaled on the shaft of the object to be revolved and hence retard or arrest the rotation of the object, upon the next pull upon the cord for retensioning the spring employed to effect rotation of the object.

My object is to produce a toy of this general class which is of such construction that the rotation of the drum to store up power in the spring for continuing the revolution of the object shall have no appreciable retarding action upon the latter.

Another object is to produce a toy of the class outlined in which the rotation of the object can be maintained and accelerated when desired, and which embodies the desirable features of simplicity, compactness, strength and durability.

With these general objects in view, the invention consists in certain novel and peculiar features of construction and combinations of parts as hereinafter described and claimed; and in order that it may be fully understood reference is to be had to the accompanying drawing, in which:

Figure 1, is a view showing the object to be revolved, in side elevation and the housing and certain other parts in central vertical section.

Fig. 2, is a horizontal section on the line II-II of Fig. 1.

In the said drawing where like reference characters identify corresponding parts, 1 is a base surmounted by a box or housing 2, the top of the housing being open, if desired, to give convenient access to the inside mechanism.

A rectangular frame comprises a pair of

side bars 3, secured within and to opposite sides of the housing, a bottom bar 4 and a top bar 5, this frame stiffening the housing and incidentally providing support for certain parts hereinafter described. Formed in opposite walls of the housing at right angles to the walls braced by the frame described, are openings 6 and 7, and secured rigidly in and projecting through the latter is a sleeve 8 equipped at its outer end with a cross pin 9.

10 is a bearing block secured upon and centrally of the bottom 4 of the frame, and said block is provided with a central opening 11 for the reception of a flanged bearing socket 12, the flange being secured to and upon the block. The socket is provided internally with an upwardly tapering boss 13, having conical bearing 14 at its apex.

Vertically above the socket bearing described, the top bar 5 of said frame is provided with an opening 15 receiving a flanged bearing sleeve 16, the upper end of the same being pressed inward to form a V-shaped bearing collar 17.

18 is a vertical shaft having a tapering lower end engaging bearing 14 and extending through the bearing sleeve 16, the said shaft being diametrically reduced adjacent the plane of the V-shaped collar of bearing 16, to produce a shoulder 19 having a thin or line engagement or bearing on the said collar portion of sleeve 16 just below the point of smallest diameter of said collar portion, so that the latter shall guard against upward movement of said shaft when the same is revolved at a high rate of speed. At its upper end the shaft is shown as provided with a supporting collar 20 having one or more upstanding pins 21, and screwed upon the upper end of the shaft is an ornamental cap nut 22.

The object to be rotated is shown in this instance as a circular platform 23 resting upon collar 20 and fitting on pins 21, and retained thereon by nut 22. Secured in erect position upon the platform 23, is a plurality of figures 24, representing a series of horses bearing riders, which figures when the platform is revolved, will pass in rapid review before the operator.

A winding drum of any suitable construction and material, comprises the core portion 25 of cylindrical form, and head portions 26 and 27, the latter being of loop form for a purpose which hereinafter appears,

and said heads are respectively provided with central openings of larger diameter than shaft 18, which extends through them, and projecting upwardly from head 26 marginally of the opening therein and concentrically of and spaced from shaft 18, is a tubular stub-shaft 28 journaled in the sleeve bearing 16 and prevented from moving upward therein by the reduced portion 17 of said sleeve. A similar stub-shaft 29 depends from head 27 marginally of the opening therein and is journaled in bearing socket 12, and at its lower extremity incloses the tapering boss 13 of said bearing. By the construction shown for providing independent bearings for shaft 18 and for the drum, it will be apparent that said parts while occupying a concentric relation, are not in physical contact and hence neither offers frictional resistance to the rotation of the other.

The drum is provided at one end of the loop formed by its lower head, with a pair of ears 30, between which fits and is pivoted a pawl 31, actuated by a spring 32 to yieldingly engage a ratchet wheel 33, mounted on shaft 18 within said loop. A pull cord 34 is wound upon and secured at one extremity to the drum, and extends 30 therefrom through opening 6 in a wall of the housing, the cord being preferably provided with a knob 35 which will prevent the cord when released, from being wholly withdrawn into the box. An elastic strip 36 or any equivalent spring, is attached at one end to the drum and at its opposite end to a point fixed with respect to the housing. As shown the spring 36 extends outwardly within a tube 37 set in the wall of the housing opposite to the wall through which the pull cord extends, and the outer end of the spring is secured to the pin 9 extending crosswise through the tube.

To operate the device the button 35 is 45 grasped and pulled to impart unwinding movement to the cord and turning movement to the drum, the pawl slipping back over the teeth of the ratchet wheel without turning the latter, and as the drum is 50 turned, it winds up and therefore stretches or tensions the spring 36. As the pulling operation, which may be a few inches or any distance convenient for the operator, is ended, the hand grasping the button is 55 moved toward the device to relax the cord and permit the spring to retract and impart reverse rotation to the drum, and hence through the instrumentality of the pawl, cause the ratchet wheel to revolve rapidly 60 in the reverse direction to that imparted to the drum by pulling on the cord, this rotation of the drum being transmitted through the shaft 18 to the platform, which if of fair weight, will acquire sufficient momentum to 65 continue rotating an appreciable length of

time after the drum has been returned to normal position, as the only resistance to the rotation of the platform outside that offered by the cone bearings for shaft 18, is the slight pressure of the pawl on the ratchet 70 wheel, which pressure it may be noted, is desirable as it produces a succession of clicks which can very well appeal to a child as the hoof beats of the horses on the platform.

The rotation of the platform can be kept up and the speed thereof accelerated by occasionally giving the cord a pull and then permitting it to relax so as to permit the tensioned spring to perform its function in 80 the manner hereinbefore explained.

From the above description it will be apparent that I have produced a toy of the character described which possesses the features of advantage pointed out, and I wish 85 it to be understood that while I have described and claimed what now seems to be the preferred embodiment of the invention, I reserve the right to make all changes falling within the spirit and scope of the ap- 90 pended claims.

I claim:

1. A toy, comprising a housing, a shaft journaled in the housing, a drum rotatable around said shaft and out of contact therewith, a retractile spring connected to the drum and to a point in fixed relation to the housing, a pull cord connected to the drum for turning the same against the resistance of said retractile spring to tension the latter to cause it to reverse the movement of the drum when the pull on the cord is relaxed, and means for transmitting power from the drum to said shaft when the drum is turned by said spring. 95

2. A toy, comprising a housing, a shaft journaled in the housing, a drum rotatable around said shaft and out of contact therewith, a retractile spring connected to the drum and to a point in fixed relation to the housing, a pull cord connected to the drum for turning the same against the resistance of said retractile spring to tension the latter to cause it to reverse the movement of the drum when the pull on the cord is relaxed, means for transmitting power from the drum to said shaft when the drum is turned by said spring, and a platform rotatable with said shaft above the housing. 110

3. A toy, comprising a housing, a shaft journaled in the housing, a drum rotatable around said shaft and out of contact therewith, a retractile spring connected to the drum and to a point in fixed relation to the housing, a pull cord connected to the drum for turning the same against the resistance of said retractile spring to tension the latter to cause it to reverse the movement of the drum when the pull on the cord is relaxed, a ratchet wheel mounted on said 125

shaft, and a spring-actuated pawl carried by the drum and engaging said ratchet wheel.

4. A toy, comprising a housing, a frame 5 therein, a socket bearing carried by said frame, a sleeve bearing mounted in said frame vertically above the socket bearing and provided with a reduced V-shaped portion, a shaft journaled in the socket bearing and bearing against the underside of the V-shaped portion of the other bearing, and having a diametrically reduced portion extending up through said V-shaped portion of the bearing, a drum fitting around said 10 shaft, and provided at its upper end with a tubular stub shaft fitting in the said sleeve bearing concentrically around and out of contact with the first-named shaft, and pro-

vided at its lower end with a depending tubular stub shaft journaled in the socket bearing and concentrically surrounding and out of contact with the first-named shaft, a pawl and ratchet wheel connection between said drum and first-named shaft, a pull cord to rotate the drum in one direction, and a spring to be tensioned by the rotation of the drum by the cord, for the purpose of reversing the rotation of the drum when the cord is released and transmitting power through said pawl and ratchet wheel connection, from the drum to said first-named shaft. 20 25 30

In testimony whereof, I affix my signature.

JAMES E. JEWELL.
